UNITED STATES PATENT OFFICE.

ARTHUR H. SYMONS, OF CHICAGO, ILLINOIS.

HEAD MEMBER FOR SHORES.

Application filed August 22, 1925. Serial No. 51,764.

The present invention relates to head members for shores.

Shores such as are used for building construction are elongated members, and in order that the bearing area at the extremity may be relatively large, it is common to provide a head member. Head members for the purpose are frequently very bulky, and the cost of transportation and handling is relatively high. Head members as commonly known and used have the further disadvantage that they are heavy, inconvenient in use, and are frequently insecure.

An object of the present invention is to provide a head member for a shore, which head member will fit the common type of shore, which may conveniently be secured thereto, and which may conveniently be detached therefrom.

A further object is to provide a head member for shores which is sturdy, light in weight and small in bulk.

A further object is to provide a mountable head member for a shore, which will stand long continued hard usage without material depreciation, and which is adapted for use with holding means such as are readily procurable in the market.

A further object is to provide a head member for shores which is cheap to manufacture and which will effectively serve the needs of commercial operation.

Further objects will appear as the description proceeds.

Referring to the drawings—

Figure 1 is a fragmentary view illustrating a portion of a shore, a member supported by said shore and a head member for said shore, which head member embodies the principles of the present invention.

Figure 2 is a view in side elevation, partly shown in section, of the structure shown in Figure 1.

Figure 3 is a bottom plan view, the shore being shown in section, of the structure shown in Figure 1.

Figure 4 is a sectional view taken along the plane indicated by the arrows 4—4 of Figure 1.

Figure 5 is a sectional view taken along the plane indicated by the arrows 5—5 of Figure 3.

Figure 6 is a sectional view taken along the plane indicated by the arrows 6—6 of Figure 1.

Figure 7 is a perspective view of a spike

or nail of common type which may be used in the practice of the present invention.

A shore is indicated by the numeral 1, which shore is indicated in the usual form as including an elongated timber of square cross-section. Timbers known in the art as "4x4's" are commonly used. A member to be supported is indicated by numeral 2. In order to provide a broad bearing surface, the shore 1 is provided with a head member, which is indicated as a whole by the numeral 3. Said head member, according to the present invention, involves a socket portion for receiving an extremity of the shore 1, and is provided with a broad bearing portion for contact with the member to be supported. According to the present invention, the socket portion referred to is of novel conformation and cooperates with nails or spikes of well-known construction or other wedge-shaped members for securely holding the head member 3 upon the end of the shore.

The socket portion referred to for receiving the end of the shore 1 is indicated on the drawings by the numeral 4. Said socket portion 4 has the opposed side walls 5—5, which may have substantially plane inner surfaces spaced apart a sufficient distance to slidably receive the shore 1. The intermediate opposed walls 6—6 are provided with the grooves 7—7, two grooves 7—7 being illustrated in each of the walls 6—6. Said walls 6—6 are spaced apart a sufficient distance to slidably receive the shore 1, and the grooves 7—7 are adapted to receive nails or other wedge-shaped members 8—8. The upper part of the socket portion 4 is provided with the inturned walls 9—9, which are disposed upon the end of the shore 1 and provide stops for preventing head member 3 from sliding downwardly upon the shore 1. Socket portion 4 is provided with the outstanding flanges or wings 10—10, which may be reinforced by means of ribs 11—11. The head member 3 may be cast or forged steel or iron and should be of sufficiently tough and strong material to avoid breakage in service.

The nails or other wedge-shaped members 8—8 are preferably of more than sufficient length to extend through both side walls 5—5 of the socket portion 4, apertures 12—12 being provided in said side walls 5—5 for permitting the passage of said members 8—8. The grooves 7—7 should be of such a depth, and the size of the members 8—8 should be

such, that when members 8-8 are inserted along one side of the socket portion 4, said members will, guided by the grooves 7-7, jam the material of the shore 1 to such an extent that the head member 3 will be secured against removal from the shore 1. The walls 6-6 will be spaced apart at such a distance that when a new timber is being used, members 8-8 on only one side of the socket portion 4 will be sufficient to produce all the locking action required. When old timbers are being used, it may be found advantageous to use members 8 on both sides of the socket portion 4.

15 It has been stated above that the nails or other wedge-shaped members 8-8 should be of more than sufficient length to extend through the two side walls 5-5 of the socket portion 4. By reason of this construction, after said members 8-8 are driven home, the removal thereof is greatly simplified, it being a simple matter to tap same on the point ends thereof. In order to simplify the matter of removal of the members 8-8, it is preferred to use tapered nails, the type known as "cut" nails being readily purchasable in the open market and being very well adapted for this purpose, though, of course, any other preferred wedging member may be used if desired. By reason of the tapered construction, when said nails are tapped at their point ends, they will become freed from the material of the timber to a sufficient extent that said nails may be readily removed without the use of any particular tools for that purpose. The nails or other wedging members 8-8 have a biting effect upon the wooden shore, and therefore produce a locking effect to prevent axial movement between the head member and the shore.

45 The present invention provides a head member for shores which provides a broad bearing surface, which is relatively light in weight, small in bulk, and which may be attached to a shore and detached therefrom with a maximum of convenience. The life of the illustrated embodiment of the present invention should be practically unlimited, provided tough material is used in the manufacture thereof. Inasmuch as "cut" nails suitable for the purpose of attaching the head member to the shore may be read-

ily purchased anywhere in the United States, no difficulties due to wear on nails 55 need be encountered. The problem of transporting the head members is very greatly simplified, it being possible to carry sufficient head members for a large job in a single truck.

60 Though a preferred embodiment of the present invention has been described in detail, many modifications will occur to those skilled in the art. It is intended to cover all such modifications that fall within the 65 scope of the appended claims.

What is claimed is:

1. In combination, a wooden shore, a head member therefor, and attaching means for attaching said head member to said shore, 70 said head member comprising a bearing portion and a socket portion, said socket portion being square in cross section, opposed inner walls being parallel with one another, one of said inner walls being provided with a groove and a wedging member extending beyond the extremities of said socket portion, said wedging member being disposed in jamming relationship between said socket portion and said shore, whereby 75 to have a biting effect upon said wooden shore to produce a locking effect to prevent axial movement between said head member and said shore.

2. In combination, a wooden shore, a head 80 member therefor, and means for attaching said head member to said shore, said head member comprising a socket portion square in cross section, opposed walls being parallel, the four walls defining said square cross 85 section being adapted to cooperate with the sides of said shore, said socket portion having a portion adapted to abut against the end of said shore, two of said four walls being substantially plane, another of said 90 walls being provided with a groove, said attaching means comprising a wedging member adapted to lie in said groove and to have jamming relationship with said other wall and said shore, said wedging member being 95 of such length that the extremities thereof extend beyond the outlines of said socket.

Signed at Chicago, Illinois, this 18th day of August, 1925.

ARTHUR H. SYMONS.
